ABSTRACT

A hatch cover including a multiplicity of relatively narrow cover panels of L-shaped cross-section which are laid over a hatch coaming having a panel storing station at one end thereof, with their longer legs placed side by side horizontally thereon and with their shorter legs depending as skirt portions in hatch closing position. A scooping support carriage is provided for supporting the weight of all cover panels loaded thereon in superposed manner while scooping up one panel after the other progressively during a movement of the carriage so as to bring them from a hatch closing position to a panel storing position during hatch opening operation, and vice versa. The carriage is provided with cam means for actuating push rod members slidably mounted on each cover panel upwardly so as to elevate an adjoining cover panel at a level higher than that of the former panel as a first move for bringing the latter panel into superposed condition over the former panel, in addition to another cam means for holding all of the cover panels loaded thereon in superposed condition one above the other.

HATCH COVERS

The present invention relates to a hatch cover, and more particularly to a hatch cover including a plurality of cover panels of substantially L-shaped cross-section movable between hatch closing and opening positions by means of a support carriage with each panel being loaded on or unloaded from the carriage one after the other during a movement of the carriage.

A hatch cover using such a scooping support carriage is known in the prior art. However, the carriage means for carrying a multiplicity of cover panels of L-shaped cross-section loaded thereon is complicated in its construction and not easily operated. The present invention contemplates to improve the structure and operation of the prior art hatch cover of this kind.

It is a primary object of the present invention to provide a hatch cover including plurality of cover panels of substantially L-shaped cross-section moved smoothly between hatch closing and opening positions by means of a support carriage which is simple to construct and easy to operate.

It is another object of the present invention to provide a hatch cover having a plurality of cover panels of substantially L-shaped cross-section which are positively interconnected one with the other so as to be held together in one block during closed condition.

It is still another object of the present invention to provide a hatch cover including a plurality of cover panels of substantially L-shaped cross-section which are constructed so as to be smoothly separated from each other during hatch opening operation by means of push rod members slidably mounted on each panel and actuated by cam means provided on the carriage for positively disengaging adjoining panels from each other.

According to the present invention, there is provided a hatch cover having a plurality of narrow cover panels of substantially L-shaped cross-section connected together on horizontal support members on a hatch coaming and each extending laterally with respect to a direction of hatch opening operation, including push rod members slidably mounted on each panel adjacent to a corner portion of the L-shaped cross-section thereof for lifting up an opposed edge of the adjoining panel, and a support carriage located below and connected to one of said cover panels placed adjacent to one end of said hatch coaming in the closed condition and having wheels rolling along rail members on the hatch coaming so as to move said carriage back and forth between said one end and the opposite end of the hatch coaming with said cover panels loaded thereon in superposed manner, said support carriage being provided with first cam means engageable with a skirt portion of each panel and with second cam means for actuating said push rod members on each panel upwardly.

Now, one preferable embodiment according to the present invention will be described hereinafter in detail by way of example with reference to the accompanying drawings, in which,

FIG. 1 is a plan view showing a hatch opening provided with hatch cover panels according to the present invention,

FIG. 1A is a section view taken along a line A—A in FIG. 1,

FIG. 1B is a section view taken along a line B—B in FIG. 1,

FIG. 1C is a section view taken along a line C—C in FIG. 1,

5 FIG. 1D is a section view taken along a line D—D in FIG. 1,

FIG. 1E is a plan view showing the hatch coaming with cover panels removed,

10 FIG. 2A is a side elevation view showing the a support carriage,

FIG. 2B is a plan view showing the support carriage in FIG. 2A,

15 FIG. 3 is a side elevation view showing the cover panels and the support carriage in hatch closing position,

FIG. 4 is a side elevation view showing the cover panels and the support carriage during hatch opening operation,

20 FIG. 5 is a side elevation view showing the cover panels and the support carriage in stored position after hatch opening operation,

FIG. 6A and 6B are detailed section views in enlarged scale showing an interconnecting means between a pair of adjoining cover panels, FIG. 6A showing the position of an interconnecting pawl member when a hatch opening operation is commenced, and FIG. 6B showing the position of the same during hatch closing operation,

30 FIG. 7 is a side elevation view showing the position of a plurality of the pawl members during hatch opening operation,

FIG. 8 is an end view in enlarged scale showing the relative position of a wing end portion of each panel, a push rod member, and the support carriage,

35 FIG. 9A is a plan view showing another embodiment of interconnecting means between two adjoining panels,

FIG. 9B is a plan view in enlarged scale showing the interconnecting means in FIG. 9A.

FIG. 9C is a side elevation view in enlarged scale showing the same, and

FIG. 10 is a view similar to FIG. 8, showing a link member interconnecting two adjacent panels in FIG. 9a, 9b, 9c.

45 Referring to FIG. 1, 1A, 1B, 1C, 1D and 1E, there are shown a number of elongated cover panels 2A, 2B, 2C...2M of substantially L-shaped cross-section supported flatly on a horizontal top surface of side coamings at both ends thereof so as to cover an opening of hatch coaming 1. As shown in FIG. 1B, each L-shaped cover panel includes a longer leg which constitutes a covering surface for the hatch opening and a shorter leg depending therefrom to form a skirt portion. Each panel is provided adjacent to a corner portion of the L-shaped cross-section with a flat bar 4 so as to support the free edge of the adjoining panel. Movable support carriage or cradle means 5 are placed on horizontal support members 3 on both sides of the hatch coaming 1, as shown in FIG. 1E from which all the cover panels 2A, 2B, 2C,...2M are removed. The movable support carriage 5 is placed oppositely to the end coaming with its substantial portion located below the extreme left end panel 2A when all the panels are in hatch closing position (SEE FIG. 3). As will be described in detail hereinafter, the movable carriage 5 will support all the panels 2A, 2B, 2C.... which are loaded thereon in superposed manner after scooping up one panel after the

50 55 60 65 65

other while it makes a transit and bring them to the storing position as shown in FIG. 5 wherein all the panels are removed from the hatch opening.

As shown in FIG. 2A, the support carriage 5 is tapered to facilitate a scooping operation and provided with a suitable number of wheels 8, 8' rolling on the hatch coaming 1 and also with first and second cam surface 6 and 7 which will be described in detail hereinafter. The support carriage 5 is connected to the extreme left end cover panel 2A by means of a link member 9 having one end pivotally mounted on the carriage 5 by a pin 10 and the other end pivoted to a lug piece 12 on the cover panel 2A by another pin 11. Hence, the carriage 5 will move together with the extreme left end cover panel 2A although the former may be moved slightly with reference to the latter.

The link member 9 will raise the panel 2A on the left side and bring it into tilted position as shown in FIG. 5 when the support carriage 5 is moved to the right relative to the panel 2A. Support carriages 5, 5 on both sides are connected together by suitable connecting means, although this means is not shown in the drawing.

As shown in FIG. 3, 4, 5 and 8, push rod members 13A, 13B, 13C are slidably mounted respectively on each cover panels 2A, 2B, 2C, ..., at both ends thereof adjacent to the corner portions of L-shaped cross-section. The push rod 13A loosely passing through a guide member 14A secured to the cover panel 2A has its upper end in contact with the lower surface of the left end of the adjoining panel 2B which is placed oppositely to the panel 2A (see FIG. 3). When the support carriage 5 is moved to the right from the extreme left end position, that is, the closed position of cover panels in FIG. 3, the push rod 13A will come into contact with the second cam surface 7 of the support carriage 5 at the lower end thereof and hence is pushed upwardly by the latter. Accordingly, the push rod 13A will lift up the left end portion of the adjoining panel 2B and elevate it at a level higher than that of the corner portion of the panel 2A. This operation will become a first move for bringing the panel 2B into superposed position over the panel 2A. FIG. 4 shows the support carriage 5 making a transit and the push rod 13B on the cover panel 2B which is pushing up the left end portion of the following panel 2C.

On the other hand, a shorter leg or vertical flange of L-shaped cross-section of each panel is provided at both wing ends with notched wing portions 16A, 16B, 16C, ..., as shown in FIG. 8. Those notched wing portions 16A, 16B, 16C, ..., will come successively into contact with the first cam surface 6 of the support carriage 5 at their lower edges when the support carriage 5 moves to the right and then become engaged with stepped edges of the first cam surface 6. Each of these stepped edges of the first cam surface 6 will act as stopper means for preventing each panel from being pressed unduly to the left by action of the following panels which are superposed thereon. Operative position of the panel 2B with respect to the panel 2A has been described hereinabove. However, the mutual position during operation is similar between any other pair of adjoining panels, such as panels 2C and 2D.

FIG. 5 shows the support carriage 5 carrying all of the cover panels loaded thereon in the extreme right end position, that is, the panel storing position. In this position, both side notched wing portions 16A, 16B,

16C, ..., of each panel become engaged with stepped portions of the first cam surface 6 of the support carriage 5 at lower edges edges of the skirt portion and lower ends of the push rod members 13A, 13B, 13C, ..., are engaged with stepped portions of the second cam surface 7. The extreme right end panel 2M is pivoted about a pin 15, which pivotally mounts the panel 2M on the hatch coaming 1 through intervention of a suitable lug piece 25.

10 As shown in FIGS. 6A and 6B, a pawl member 17 is provided on each panel 2A, 2B, 2C, ..., for interconnecting each of them to the adjoining panel. The pawl member 17, which has a pointed hook end 17N, is slidably inserted into socket means 21 mounted on each panel 2A, 2B, 2C, ..., The pawl member 17 is provided adjacent to an upper end thereof with a slot 19, which has a pin member 20 passed there through. The pin member 20 is secured on a skirt portion 2S of the panel 2A. A coil spring 23 is inserted between a flange portion 22 provide on the pawl member 17 adjacent to a lower end thereof and a lug piece 24 mounted on the skirt portion 2S of the panel 2A, so as to normally urge the pawl member 17 into raised position. The pointed hook end 17N of the pawl member 17 is inserted into an opening 18 on the adjoining panel 2B provided adjacent to a left edge thereof so as to interconnect the panel 2A to the panel 2B (FIG. 6A). Since the panel 2A is moved to the right, that is, toward the panel 2B during hatch opening operation, the pointed hook end 17N will come into contact with righthand wall surface of the opening 18 as shown in FIG. 6A. Since the panel 2A is moved to the left, that is, away from the panel 2B during hatch closing operation, the pointed hook end 17N will come into contact with lefthand wall surface of the opening 18 (see FIG. 6B). Since the panel 2B is disengaged out of the pointed hook end 17N and superposed over the panel 2A, righthand surface of the pointed hook end 17N is rounded off and the wall surface of the opening 18 is correspondingly tapered in the righthand portion to facilitate the disengagement of the pointed hook end 17N out of the opening 18. Conversely, since the panel 2A must be positively connected to the panel 2B during hatch closing operation, the pointed hook end 17N is slanted on the left side so as to be securely engaged with the opening 18 which is provided with a complementary slanted wall surface.

FIG. 7 shows several cover panels in transit having pawl members 17 as illustrated in FIGS. 6A and 6B. Both panels 2B, 2C are separated away from the pawl members 17 and overlapped on the adjoining lefthand panels.

FIG. 8 shows the relative position between the side coaming 1 and the notched wing portions 16A, 16B, 16C, ..., of each panel. The first cam surface 6 of the support carriage 5 is engaged with the lower edge of each of notched wing portions 16A, 16B, 16C, ..., The second cam surface 7 is in contact with lower end of each of push rod members 13A, 13B, 13C, ..., as described hereinabove. And, the pointed hook end 17N of the pawl member 17 is engaged with the opening 18 of the adjoining panel.

FIGS. 9A, 9B and 9C show a modified form of the interconnecting means between a pair of adjoining panels. Each one of cover panels 2A, 2B, 2C, 2D, ..., is connected to the adjoining panel respectively by means of link bars 26B, 26C, 26D, ... Both ends of each link bar are secured to the skirt portions of two adjoining panels.

els. The link bar 26A is connected at one end to the panel 2A by means of a ring fitting 27B secured to the skirt portion of that panel and at the other end to the adjoining panel 2B by means of a ring fitting 28B secured to the skirt portion of the same panel. Since the link bar 26A is held between skirt portions of two adjoining panels 2A, 2B, which are superposed one above the other, during hatch opening operation, it is provided with an articulated joint 30 so as to accommodate a change of spacing between two skirt portions of adjoining panels. A turnbuckle means 29 is inserted into the link bar 26A so as to adjust the total length of the latter.

In describing the operation of the hatch cover, it is assumed that all panels are initially placed in hatch closing position with the extreme left end panel 2A having its left side edge laid over the end coaming and with the support carriage 5 located underneath the panel 2A (see FIG. 3). When the carriage 5 is moved to the right for opening the cover panels by pulling a wire 31, the link 9 will be pivoted counterclockwise about the pin 10 until it is erected substantially upright as shown in FIG. 5. Hence, the panel 2A will be tilted with its lefthand edge elevated at a level higher than that of the opposite edge. When the carriage 5 is moved further to the right, the first cam surface 6 of the carriage 5 will come into contact with notched wing portions 16A of the panel 2A at both ends and will have stepped portions 32A (FIG. 3) engaged with those notched wing portions 16A. Simultaneously, the second cam surface 7 of the carriage 5 will actuate the push rod member 13A which is slidably mounted on the panel 2A adjacent to the corner portion of L-shaped cross-section, in an upward direction. Consequently, the left hand edge of the panel 2B which is in contact with the upper end of the push rod member 13A will be raised upwardly. Since the panel 2A is moved to the right together with the carriage 5 at this time, the panel 2B will be superposed on the panel 2A. Similar operation will occur with respect to each of other panels (FIG. 4). Then, the carriage 5 will carry all of the panels 2A, 2B, 2C..... loaded thereon in superposed manner and will finally bring them to the storing position (FIG. 5).

In the closing operation, the carriage 5 located at the storing positions as shown in FIG. 5 is moved to the left by pulling a wire 33. Then, each panel is placed on the horizontal top surface of the hatch coaming one after the other commencing from the right end panel. At this time, the openings 18 provided on the lefthand edge of each panel will become engaged with pawl members 17 on the adjoining panel so as to interconnect each panel positively to the adjoining panel in the case of the interconnecting means as shown in FIGS. 6A and 6B being used. When the interconnecting means as shown in FIG. 9A, 9B and 9C is incorporated instead, each of the link bars 26B, 26C, 26D..... held between two adjoining panels will be extended so as to hold each panel at a predetermined spacing from the adjoining one. In this manner, all of the panels will be placed in hatch closing position when the carriage 5 is brought back to the position as shown in FIG. 3.

According to the present invention, since the support

carriage 5 is provided merely with the first and second stepped cam surface 6, 7, eliminating any kind of rotating member, such as rotatable cam means, the handling mechanism for the cover panels will become simple to construct and easy to operate. Therefore, the cost of construction and maintenance can be reduced considerably.

What is claimed is:

1. A hatch cover for a hatch opening comprising: a plurality of cover panels disposed in side by side relationship over the hatch opening in a hatch closed position and movable in a direction along the hatch opening into a superposed array at a hatch open position; each of said cover panels including a portion extending downwardly therefrom; a push rod member slidably mounted on each cover panel and disposed beneath an adjoining panel for selectively lifting said adjoining panels; a support carriage located below said cover panels and movable in said direction along the hatch opening; said support carriage including cam means sequentially engageable with each of the downwardly depending portions of said cover panels for advancing same toward the hatch open position; said support carriage further including cam means having a sequence of stepped portions descending in the direction toward the hatch open position and being sequentially engageable with each of said push rod members for actuating same into lifting contact with each of said adjoining panels such that the cover panels may be advanced under the lifted adjoining cover panels.
2. A hatch cover for a hatch opening comprising: a plurality of cover panels disposed in side by side relationship over the hatch opening in a hatch closed position and movable in a direction along the hatch opening into a superposed array at a hatch open position; each of said cover panels including a portion extending downwardly therefrom; a push rod member slidably mounted on each cover panel and disposed beneath an adjoining panel for selectively lifting said adjoining panels; a support carriage located below said cover panels and movable in said direction along the hatch opening; said support carriage including cam means having a sequence of stepped portions descending in the direction toward the hatch open position and being sequentially engageable with each of the downwardly depending portions of said cover panels for advancing same toward the hatch open position; and said support carriage further including cam means sequentially engageable with each of said push rod members for actuating same into lifting contact with each of said adjoining panels such that the cover panels may be advanced under the lifted adjoining cover panels.
